GUARD FOR RAZORS AND HAIR CLIPPERS

Ferdinand F. Starr, New York, N. Y.

Application July 19, 1938, Serial No. 219,941

3 Claims. (Cl. 30—90)

This invention relates to guards for the type of shaving apparatus commonly known as a "dry shaver."

The shaving head of certain kinds of such apparatus consists of a skin-contacting plate having a series of slots forming blades between the slots and a cutter having a plurality of cutting edges located beneath the plate. Cutting of hair is effected by a shearing action produced by relative reciprocation of the plate and the cutter and the co-action of the blades of the plate and the cutting edges of the cutter. In many such devices the plate is flat and the blades exhibit rather sharp projecting ends which tend to dig into and scrape the skin and thereby produce irritation, this effect being increasingly accentuated as the angle of the implement with respect to the surface being shaved increasingly departs from a perpendicular position with respect thereto.

The principal object of my invention is to equip such apparatus with means for preventing these objectionable effects. The object is accomplished by providing means to be attached to the apparatus which will cause a smooth travel of the plate over the skin, both by stretching the wave of skin in advance of the plate and by reducing the pressure of the projecting ends of the blades on the skin.

30 Referring to the drawing,

Fig. 1 is a perspective view of the type of shaving apparatus referred to, with my device attached thereto;

Fig. 2 is a broken view on the line 2—2 of Fig. 1;

Fig. 3 is a view on the line 3—3 of Fig. 1 with part of the casing however not shown;

Fig. 4 is a perspective view of my device;

Fig. 5 is an obverse view of Fig. 3.

40 Describing the drawing more specifically, the dry shaver itself consists of a casing 1 which serves as a handle and also encloses the motor and driving parts for actuating the cutting members. The cutting head consists of the hollow stationary member 2 comprising a flat skin contacting plate consisting of the blades 3 and the inner cutter 4. The inner cutter is caused to reciprocate by the vibratory motion of the lever 5, which motion is effected by suitable actuating 45 connection with the motor, but, as the nature of such a connection is well known in the art and as its details are not important so far as my invention is concerned, it will not be further described. The blades of the skin-engaging plate 50 usually project as shown at 6 forming a multi-

tude of sharp points which are, as has been before noted, the cause of considerable skin irritation when the device is being used for the intended purpose, the intensity of this skin irritation increasing as it is tipped from a position 5 perpendicular to the surface being shaved.

In order to prevent this undesirable effect, I mount on each side of the skin-engaging plate a series of balls 7 and 8 carried in ball containers 9 and 10 and confined therein, although 10 loosely enough to permit them to freely rotate in all directions, by tipping over the edges of the channel sections of the container as shown at 11. The balls are prevented from leaving the channels at their ends by tipping over the portions 12 15 of the channels and the channels are connected together as shown at 12a and 12b.

As a means of locating and attaching my device to the shaving apparatus so that the two series of balls are properly located to serve as a 20 guard and are in proper relation to the plate, I provide one of the channels—for example, the channel 10, with a tongue 13 slotted as shown at 14, which slot engages with the shank of a set screw 15. This set screw is a standard part of a 25 certain kind of dry shaving apparatus in connection with which I propose to use my device, but, in the absence of such a set screw, any projection will serve as well. The other channel 9 may be provided with a depending tongue 16 30 adapted by its construction to engage with apertures 17 and 18 in the casing. Such apertures are characteristically found in the type of shaving apparatus to which I have above referred, but, in their absence may be provided, or projections 35 may be utilized for the same purpose. The tongue 16 in this particular case is bifurcated as shown in order that it may engage with both the apertures 17 and 18, and be thereby anchored, by turning over the ends until they form complete or partial hooks, as shown at 19, Fig. 2. It is best that the engagement of the hooks with the apertures be releasable by merely exerting a strain on the tongue 16 and for this purpose the partial hooks are preferable. In this way the 40 device may be not only attached to the shaving apparatus by slipping it down over the plate but may be also detached therefrom by merely exerting a manual pull.

It will be seen that, since each ball composing 50 the guard can rotate in any direction, the device provided with such guards can also be moved across the face of a user in any direction—i. e., transversely to the ball channels, lengthwise of them, or in any direction between these two and 55

still utilize the rotative action of the balls. This is an advantage since most users of dry shavers do not confine themselves to a motion that is parallel with the blade slots but, on the contrary, find that shaving can be effectively accomplished by moving the implement in various directions.

While I have described certain particular embodiments of my invention, I do not desire to be limited to these particular embodiments since many changes and modifications may easily be made without departing from the spirit and scope of the invention as set forth in the following claims.

15 I claim:

1. A guard device for a razor of the type characterized by a shaving head that includes a skin-contacting plate mounted on a handle, said guard device comprising two parallel connected guards spaced to permit the location therebetween of said shaving head and also provided with a tongue adapted to engage an anchorage located on the said handle each of said guards

comprising a channel with a series of balls confined therein.

2. A guard device for a razor of the type characterized by a shaving head that includes a skin-contacting plate mounted on a handle provided 5 with an aperture in one side, said guard device comprising two parallel connected guards spaced to permit the location therebetween of said shaving head and also provided with a tongue terminating in a hook adapted to engage said aperture, each of said guards comprising a channel with a series of balls confined therein.

3. A guard device for a razor of the type characterized by a shaving head that includes a skin-contacting plate mounted on a handle, said 15 guard device comprising two parallel connected guards spaced to permit the location therebetween of said shaving head and also provided with a tongue terminating in a hook adapted to engage an aperture in the side of said handle, 20 each of said guards comprising a channel with a series of balls confined therein.

FERDINAND F. STARR.
